FISHERMAN'S KNIFE

Julius Feist, 141 W. 73rd St., New York, N.Y.

Filed Mar. 7, 1962, Ser. No. 69,134

Term of patent 14 years

(Cl. D22—3)

FIG. 1.

FIG. 4

FIG. 2.

FIG. 3.

FIGURE 1 is a perspective view of a fisherman's knife showing my design as it appears with the parts thereof in open position.

FIGURE 2 is an end elevational view as seen on line 2—2 of FIGURE 1 with the tape measure in retracted position.

FIGURE 3 is a cross-sectional view taken on line 3—3 of FIGURE 1.

FIGURE 4 is a bottom plan view thereof as seen looking in the direction of the arrows 4—4 on FIG. 1.

The characteristic features of my design reside in a knife having at its lower end a ball-like end member encasing a tape measure, all as shown.

I claim:

The ornamental design for a fisherman's knife, as shown and described.
